Primary Examiner — Kevin Rudzinski*(74) Attorney, Agent, or Firm* — Carol N. Green Kaul(57) **CLAIM**

The ornamental design for a computer screen with icon, as shown and described.

DESCRIPTION

FIG. 1 is a front view of a computer screen with icon.
FIG. 2 is a perspective view of the computer screen with icon.
FIG. 3 is a second perspective view of the computer screen with icon; and,
FIG. 4 is another embodiment of the computer screen with icon.
The broken lines in FIGS. 1-4 illustrating the computer screen and portions of the icon are included for environmental purposes only and form no part of the claimed design.

1 Claim, 2 Drawing Sheets(56)
